UNITED STATES PATENT OFFICE.

SIDONIE H. KIRSCH, OF NEW YORK, N. Y.

CLEANING AND POLISHING IMPLEMENT.

Application filed September 4, 1924. Serial No. 735,963.

This invention relates to cleaning and polishing implements adapted more especially for cleaning flat surfaces such as those of windows, mirrors or the like, without the use of water. One object of the invention is to provide a body of resilient material having pores like a sponge, for example, the pores being charged with dry polishing powder, the resilient body being mounted in a suitable holder or receptacle, and the working face of the resilient body being covered by a fine mesh cleaning-cloth which is adapted to confine the powder in the pores except when preparing to polish by tapping the face of the device against the surface which is to be cleaned and polished, thereby discharging some of the powder, and making it possible for surplus powder to re-enter the pores of the resilient body. Another object of the invention is to provide cleaning and polishing means which comprises an open-mouth casing and a suitable polishing powder receptacle mounted in the casing, so that after the powder has been discharged by tapping the device against a surface, the surface may be cleaned and polished by the powder by rubbing the working face of the implement thereon, while at the same time the casing keeps the receptacle centered therein and substantially maintains its own shape.

These being among the objects of the present invention, the same consists of certain features of construction and combinations of parts to be hereinafter described and then claimed, with reference to the accompanying drawings illustrating desirable embodiments of the invention and in which:

Fig. 1 is a perspective view of the device, a handle being shown in dotted lines;

Fig. 2 is a face view;

Fig. 3 is a diametrical section of Fig. 2;

Fig. 4 is a broken side view showing the device in use;

Fig. 5 is a perspective view of a modification in which the outer casing shown in the preceding figures is omitted.

Fig. 6 is a side elevation thereof, partly broken away; and

Fig. 7 is a face view of a fragment of the device shown in Figs. 5 and 6, the cleaning-cloth being omitted.

With reference to Figs. 1 to 4 inclusive, the improved cleaning and polishing implement comprises an outer cup 10 forming a cas-

ing in which is located an inner cup 11, the cup 11 preferably being nested in the casing 10 so that the rims or mouths of the two said parts lie in, or substantially in, the same plane. Preferably the outer and inner cups are of resilient material, such as rubber for example, but yet are stiff enough to practically maintain their original shapes. Held within the inner cup or receptacle 11 is a resilient body 12 which is composed of some such porous resilient material as sponge so as to constitute a pad confined by the cup 11.

The porous resilient body 12 forms a powder container, the pores of which are adapted to receive charges 13 of dry cleaning and polishing powder. The powder may be of any composition suitable for dry cleaning and polishing. A fine mesh cleaning-cloth 14 of suitable size and material is provided, and this cloth is secured by a band 15 around the rim of the inner cup and a band 16 around the rim of the outer cup or casing. These two bands are preferably composed of rubber so that the cleaning cloth may be easily removed when desired, as for charging the pores of the resilient body 12 with powder, although the charging with powder may be performed in any other suitable manner. Preferably the rims of the inner and outer cups are respectively provided with annular grooves 17, 18, to receive the cloth 14 where it is held by bands 15, 16 and to secure the cloth properly.

The described cleaning implement may be provided with a suitable handle 19, indicated in dotted lines, which may be held at its inner end in a socket 20 at the back of the outer cup or casing 10, so that all points of the outer surface of a window, for example, may be rendered accessible to the cleaning and polishing instrumentalities. In preparing to use the implement the operator grasps the handle 19, or, if such handle is not provided, grasps the back portion of the outer cup or casing 10 and taps the cloth face of the implement against the window, mirror or the like which is to be cleaned and polished. A number of taps may be necessary, and the tapping will result in a discharge of powder, from the container provided by the porous resilient body 12, through that portion of the cleaning-cloth which extends over the inner cup 11. A rubbing motion is then imparted to the im-

plement and upon the window, mirror, etc., and with the assistance of the cleaning cloth and concomitant parts acts to clean and polish that surface of the window, etc., 5 which is being rubbed. This is accomplished without the wetting of the powder or the surface to be cleaned.

It will be understood that in this embodiment of the invention, the act of tapping against a surface will cause the inner cup and the part of the cleaning cloth there-over to be momentarily projected slightly in advance of the outer casing 10 so that the powder may be applied conveniently without danger of breaking the glass. In rubbing, the mouths of the inner and outer cups will lie approximately in one plane and the portions of the cloth which pass over the rims of the cups will be utilized to produce 15 the effective pressure, although it is obvious that the device may be modified in this connection so that this relative position is not actually the case. It is probable that any surplus powder on the window, mirror, etc., 20 will largely if not entirely re-enter the device by going into the crease or groove of the cloth where it is confined between the rims of the two cups 10, 11. It will be evident that, when the inner cup is pressed 25 back into the outer cup during the polishing operation on glass, there is very little air space between the cups and, when the outer cup is drawn away from the glass, the inner cup will tend to move out and to increase 30 the air space between the cups and to draw in air between the rims of the cups. The suction thus created will tend to draw 35 through the cloth and into the air space surplus powder collected just outside the rim 40 of the inner cup. It is obvious that the proportions of the parts of the implement may be varied as desired and that the two cups may be made of other shapes instead 45 of the circular shape shown. For example, the shape may be square, oblong or any other shape which will facilitate the cleaning of the square corners of windows or mirrors.

In the modification shown in Figs. 5 and 50 6 the outer casing 10 of Figs. 1 to 4 is omitted. In this modification there is provided a cup or receptacle 21, in which is positioned a porous resilient body 22 and over the face of the body 22 and the rim of the cup 21 there is secured a fine mesh cleaning-cloth 55 23 which may be held to the cup by a band 24, these parts practically corresponding with the similar parts shown in Figs. 1 and 4 inclusive. In this case the rim of the cup 21 is tapped gently against the surface to be cleaned and the powder in the pores of the body 22 will be discharged through the meshes of the cleaning cloth.

65 The foregoing detailed description has been given for clearness of understanding,

and no undue limitation should be deduced therefrom, but the appended claims should be construed as broadly as possible, in view of the prior art.

What I claim as new and desire to secure 70 by Letters Patent is:

1. A cleaning and polishing implement, comprising a casing with an open face, a body of porous resilient material chargeable with polishing powder, a receptacle for such body positioned in said cup and having an open face adjacent the open face of the casing, and a fine mesh cleaning-cloth fastened to said receptacle to cover the open face thereof and fastened loosely over the 75 rim of said casing to permit the receptacle to be pressed into the casing while polishing and to move outwardly therefrom when released, thereby producing suction to draw into the space between the receptacle and 80 the casing surplus powder remaining after polishing.

2. A cleaning and polishing implement, comprising a casing having an open face, a body of resilient material having pores charged with dry polishing powder, a fine mesh cloth loosely covering the open face of the casing and secured to the edge of the casing around said open face, and material 90 enclosing said body of resilient material at the rear and attached to said fine mesh cloth around the periphery of said porous body to support the same from the cloth, such attachment being along a line spaced from the rim of said open face to provide slack in the cloth to permit limited movement of said body into and out of said casing.

3. A cleaning and polishing implement, comprising an outer cup forming a casing, 105 a receptacle for polishing powder therein, and a fine mesh cleaning-cloth secured to the receptacle and by which the powder is confined except when desired for use, said cloth being also secured to the outer cup and loosely supporting the receptacle in 110 said cup.

4. A cleaning and polishing implement, comprising an outer cup forming a casing, 115 an inner cup forming a receptacle for polishing powder, and a fine mesh cloth secured to the inner cup over the mouth thereof, and means for securing the cups together, and allowing of freedom of movement of the inner cup in the outer cup.

5. A cleaning and polishing implement, comprising an outer cup forming a casing, 120 an inner cup, movable in the outer cup, a body of resilient material placed in the inner cup and having pores chargeable with polishing powder, and a fine mesh cleaning-cloth to which the inner cup is secured and by which the powder is confined except when desired, said cloth being also secured to the outer cup.

6. A cleaning and polishing implement,

comprising a body of resilient porous material charged with dry polishing powder, a cup of resilient material containing said body of resilient porous material and substantially filled thereby, and a fine mesh cloth secured over the mouth of said cup and engaging said body of resilient porous material to hold it in the cup while permitting said dry polishing powder to pass therethrough when the implement is tapped against the surface to be cleaned and then

to be used for cleaning when a rubbing motion is imparted to the implement.

7. A cleaning and polishing implement, comprising two cups nested together, porous cloth over the mouths of the cups, and secured to each cup separately, the inner cup being thereby held loosely in the outer cup, and a body of resilient material in the inner cup and having pores adapted to be charged with polishing powder. ¹⁵ ²⁰
